CLAIM

The ornamental design for a front and rear engine cover alignment tool and seal installer, as shown and described.

DESCRIPTION

FIG. 1 is a perspective view of a front and rear engine cover alignment tool and seal installer according to a first embodiment;

FIG. 2 is a right side view of the invention, the left side view being a mirror image;

FIG. 3 is a front elevation view of the invention;

FIG. 4 is a rear elevation view of the invention;

FIG. 5 is a full section view of the invention;

FIG. 6 is a perspective view of the invention in use;

FIG. 7 is a perspective view of a second embodiment of the front and rear engine cover alignment tool and seal installer;

FIG. 8 is a right side view of a second embodiment of the invention, the left side view being a mirror image;

FIG. 9 is a front elevation view of a second embodiment of the invention;

FIG. 10 is a rear elevation view of a second embodiment of the invention; and,

FIG. 11 is a full section view of a second embodiment of the invention.

The broken lines in the drawings represent unclaimed environmental subject matter and form no part of the claim or features that form no part of the claimed design.
